PORTRAIT STUDIO LIGHT

James T. Aneshansley, Brooklyn, N.Y., assignor, by mesne assignments, to Berkey Photo, Inc., New York, N.Y., a corporation of Delaware

Filed June 25, 1962, Ser. No. 204,921
10 Claims. (Cl. 240—1.3)

The present invention relates to portrait studio lights, and more particularly to such lights including a light housing and a reflector with an adjustable lamp assembly.

The lamp assembly may carry an incandescent lamp or an electronic flash tube, or both, in which event the incandescent lamp may be used as a modeling light to determine the proper position and characteristics of the light produced by the electronic flash. The characteristics of the light produced may be varied by adjusting the position of the incandescent and electronic flash tubes inwardly and outwardly of the reflector.

The present invention aims to provide a portrait studio light in which the lamp assembly is adjustable with respect to the reflector.

The construction in accordance with the invention is advantageous in that the lamp assembly is readily removable from the light housing and reflector as for repair of the assembly or for substitution of another assembly.

Another object of the present invention is to provide a portrait studio light with a readily removable lamp assembly.

Other objects and advantages of the invention will be apparent from the following description and from the accompanying drawings which show, by way of example, an embodiment of the invention.

In the drawings:

FIGURE 1 is a perspective view of a portrait studio light in accordance with the invention.

FIGURE 2 is a front view of the light showing both an incandescent modeling lamp and an electronic flash tube installed in the unit.

FIGURE 3 is a rear view of the light assembly.

FIGURE 4 is a side view of the light partly in section to reveal the mechanism for adjustment of the lamp assembly.

FIGURE 5 is a side view of the pressure member 52 shown in FIGURE 4.

FIGURE 6 is an end view of pressure member 52 as seen looking from the right of FIGURE 4.

FIGURE 7 is an end view of pressure member 52 as seen looking from the left of FIGURE 4.

Referring to the drawings there is shown in FIGURE 1 a portrait studio light assembly 1 comprising a light housing 2, a reflector 3 and a supporting yoke 4 having attachment means 5 at the bottom thereof for mounting the studio light assembly on a conventional stand. The light 1 also includes a lamp assembly 6 which may carry an electronic flash tube 7 and an incandescent lamp 8. A handle 9 in conjunction with an operating rod 10 may be used to adjustably position the lamp assembly within the light housing 2.

The light housing 2 has a tubular passage 11 extending therethrough. Preferably the passage 11 may have a circular cross sectional shape although, alternatively, the passage 11 may be of rectangular or of other cross sectional shapes.

The reflector 3 may be of any conventional shape well known in the art. The light housing 2 may be formed with an outer wall 12 and an inner wall 13 to add rigidity to the construction and to provide space for engagement of thumb screws 14 or the like for securing the yoke 4 or other supporting means in position.

The lamp assembly 6 includes a socket housing 15 of

2

generally tubular shape with flat end walls 16 and 17. The shape of the socket housing 15 should be such that it will fit in the passage 11 of the light housing 2. End wall 16 may be made integrally with side wall 19. End wall

17 is removable. The side wall 19 has an opening 20 therein. The end wall 17 is apertured as indicated at 21 and has another opening 22 to receive the operating rod 10. In the end wall 16 may be formed socket means 24 to receive connection prongs 25 of the electronic flash tube 7.

A tubular member 26 extends axially of the socket housing 15 and may be made integral at one end with the end wall 16. A boss 27 is formed in the inner surface of the tube 26. An incandescent lamp socket 29 is positioned in the tube with one end abutting against the boss 27. A bracket 30 is attached to the socket 29 by a pin 30a and the bracket 30 is formed with a threaded aperture 31. The handle member 9 has a generally U-shaped bracket member 32 apertured as indicated at 34 and at 35 to respectively receive the operating rod 10 and a threaded screw member 36, the openings 35, 21 and 31 being in alignment so that the threaded screw member 36 extends therethrough providing the sole means of holding the assembly together.

A guiding channel member 40 is slideable on the outer surface of the tube 26 and is in back-to-back relationship with a channel member 41 having tapered edges 42. The channel members 40 and 41 are secured together and to flattened portion 44 of the operating rod 10 by screws 45. A spring 50 abuts between a reduced portion 51 at the end of operating rod 10 and the end wall 16 of the housing 6, one end of the spring 50 being received in a boss 50a formed in the end wall 16, the spring 50 normally tending to urge the operating rod 10 with the channel members 40 and 41 to the left so as to cause the operating rod 10 to move outwardly of the housing 6.

A pressure member 52 is formed of an arcuate shape so as to fit the opening 20 in the side wall 19 of the light housing. The outer surface of the pressure member 52 is curved to match the contour of the side wall 19. On the inner surface of the pressure member 52 are a pair of tapered grooves 54, the bottom of which conform to the angle of the tapered surface 42 so that upon an inward movement of the operating rod 10 the tapered surface 42 of the channel member 41 moves to the right so as to allow the pressure member 52 to move inwardly.

A sleeve 55 of rubber or other yieldable material is positioned around the side wall 19 and holds the pressure member 52 in position within the opening 20.

In using the studio light assembly in accordance with the invention the light characteristics of light emanating from the reflector 3 may be varied by adjustably positioning the light assembly 6 within the passage 11 of the light housing 2. The adjustment may be made by grasping the handle 9 with the fingers and pushing the rod 10 inwardly with the thumb which releases pressure between the pressure plate 52, the rubber sleeve 55 and the tubular surface 11 so that the light assembly 2 may be moved axially or rotatively and upon the release of the operating rod 10 is locked firmly in position.

While the invention has been described and illustrated with reference to a specific embodiment thereof, it will be understood that other embodiments may be resorted to without departing from the invention. Therefore, the form of the invention set out above should be considered as illustrative and not as limiting the scope of the following claims.

I claim:

1. A portrait studio light assembly comprising a light housing having a passage extending therethrough, a lamp assembly including a socket housing fitting the passage in the light housing, the socket housing having an open-

ing in the sidewall thereof, an operating rod extending into the socket housing, a tapered member secured to the operating rod, a spring tending to urge the operating rod outwardly of the housing, a pressure member fitting said opening in the sidewall of the socket housing, the pressure member having a tapered groove on the underside thereof receiving the tapered member, and a yieldable member positioned over the socket housing holding the pressure member in position.

2. A portrait studio light assembly comprising a light housing having a passage extending therethrough, a lamp assembly including a socket housing fitting the passage in the light housing, the socket housing having an opening in the sidewall thereof, an operating rod extending into the socket housing, a tapered member secured to the operating rod, a spring tending to urge the operating rod outwardly of the housing, a pressure member fitting said opening in the sidewall of the socket housing, the pressure member having a tapered groove on the underside thereof receiving the tapered member, and a rubber sleeve positioned over the socket housing holding the pressure member in position.

3. A portrait studio light assembly comprising a light housing having a passage extending therethrough, a reflector carried by the housing at an end thereof, a lamp assembly including a socket housing of generally the same shape as the passage in the light housing, the socket housing having end walls, the socket housing having an opening in the sidewall thereof, guiding means in the socket housing, a lamp socket in one end wall of the socket housing, a handle member, a guiding channel member slideable on the guiding means, a channel member with tapered edges in back-to-back relationship with the guiding channel member, an operating rod extending into the socket housing through the other end wall thereof, the channel members secured to the operating rod, a spring tending to urge the operating rod outwardly of the housing, a pressure member fitting said opening in the sidewall of the socket housing, the pressure member having a pair of tapered grooves on the underside thereof slideably receiving the edges of the tapered channel member, and a rubber sleeve positioned over the socket housing holding the pressure member in position.

4. A portrait studio light assembly comprising a light housing having a passage extending therethrough, a reflector carried by the housing at an end thereof, a lamp assembly including a socket housing of generally the same shape as the passage in the light housing, the socket housing having end walls, the socket housing having a pressure member opening in the sidewall thereof, guiding means in the socket housing, a lamp socket in one end wall of the socket housing, a bracket attached to the lamp socket and having a threaded aperture, a handle member having a pair of openings therein, one of the end walls of the socket housing having a pair of openings therein, one of the openings in alignment with one of the openings of the handle member, a threaded screw extending through said one of the openings of the handle member through one of the openings of said one end wall and engaging in the threaded aperture of the socket bracket thereby holding the assembly together, a guiding channel member slideable on the guiding means, a channel member with tapered edges in back to back relationship with the guiding channel member, an operating rod extending into the socket housing through said other end wall opening, the channel members secured to the operating rod, a spring tending to urge the operating rod outwardly of the housing, a pressure member fitting said opening in the sidewall of the socket housing, the pressure member having a pair of tapered grooves on the underside thereof slideably receiving the edges of the tapered channel member, and a rubber sleeve positioned over the socket housing holding the pressure member in position.

5. A portrait studio light assembly comprising a light housing having a passage extending therethrough, a re-

5 reflector carried by the housing at an end thereof, a lamp assembly including a socket housing of generally the same shape as the passage in the light housing, the socket housing having end walls, one of the end walls removable, the other fixed, the socket housing having an opening in the sidewall thereof, a tube axially positioned in the socket housing and attached to the fixed end wall, a lamp socket in the socket housing, means securing the socket to the tubing, a handle member, a guiding channel member slideable on the tube, a channel member with tapered edges in back-to-back relationship with the guiding channel member, an operating rod extending into the socket housing through the removable end wall, the channel members secured to the operating rod, a spring tending to urge the operating rod outwardly of the housing, a pressure member fitting said opening in the sidewall of the socket housing, the pressure member having a pair of tapered grooves on the underside thereof slideably receiving the edges of the tapered channel member, and a rubber sleeve positioned over the socket housing holding the pressure member in position.

10 6. A portrait studio light assembly comprising a light housing having a passage extending therethrough, a reflector carried by the housing at an end thereof, a lamp assembly including a socket housing of generally the same shape as the passage in the light housing, the socket housing having end walls, one of the end walls removable, the other fixed, the socket housing having an opening in the sidewall thereof, a tube axially positioned in the socket housing and attached to the fixed end wall, a lamp socket in the socket housing, means securing the socket to the tubing, a bracket attached to the lamp socket and having a threaded aperture, a handle member having a pair of openings therein, the removable end wall of the socket housing having an opening in alignment with one of the openings of the handle member, a threaded screw extending through said one of the openings of the handle member the opening of the removable end wall and engaging in the threaded aperture of the socket bracket holding the assembly together, a guiding channel member slideable on the tube, a channel member with tapered edges in back-to-back relationship with the guiding channel member, an operating rod extending into the socket housing through the removable end wall, the channel members secured to the operating rod, a spring tending to urge the operating rod outwardly of the housing, a pressure member fitting said opening in the sidewall of the socket housing, the pressure member having a pair of tapered grooves on the underside thereof slideably receiving the edges of the tapered channel member, and a rubber sleeve positioned over the socket housing holding the pressure member in position.

15 7. A portrait studio light assembly comprising a light housing having a tubular passage extending therethrough, a reflector carried by the housing at an end thereof, a lamp assembly including a socket housing of generally tubular shape with generally flat end walls, one of the end walls fixed, the other removable and having a pair of openings therein, the socket housing having an opening in the sidewall thereof, a tube axially positioned in the socket housing and integral with the fixed end wall, an incandescent lamp socket in the tube, a bracket attached to the lamp socket and having a threaded aperture, a handle member having a pair of openings therein, one of the openings in the removable end wall of the socket housing in alignment with one of the openings of the handle member, a threaded screw extending through said one of the openings of the handle member through said one of the openings of the removable end wall and engaging in the threaded aperture of the socket bracket holding the assembly together, a guiding channel member slideable on the outer surface of the tube, a channel member with tapered edges in back-to-back relationship with the guiding channel member, an operating rod extending into the socket housing through the other of said openings of the removable end wall and

through the other opening of the handle member, the channel members secured to the operating rod, a spring tending to urge the operating rod outwardly of the housing, a pressure member fitting said opening in the sidewall of the socket housing, the pressure member having a pair of tapered grooves on the underside thereof slideably receiving the edges of the tapered channel member, and a rubber sleeve positioned over the socket housing holding the pressure member in position.

8. A portrait studio light assembly comprising a light housing having a tubular passage extending therethrough, a reflector carried by the housing at an end thereof, a lamp assembly including a socket housing of generally tubular shape with generally flat end walls, one of the end walls fixed, the other removable and having a pair of openings therein, electronic flash tube socket means in the other end wall, the socket housing having an opening in the sidewall thereof, a tube axially positioned in the socket housing and integral with the fixed end walls, an incandescent lamp socket in the tube, a bracket attached to the lamp socket and having a threaded aperture, a handle member having a pair of openings therein, one of the openings in the removable end wall of the socket housing in alignment with one of the openings of the handle member, a threaded screw extending through said one of the openings of the handle member through said one of the openings of the removable end wall and engaging in the threaded aperture of the socket bracket holding the assembly together, a guiding channel member slideable on the outer surface of the tube, a channel member with tapered edges in back-to-back relationship with the guiding channel member, an operating rod extending into the socket housing through the other of said openings of the removable end wall and through the other opening of the handle member, the operating rod having a flattened end, the channel members secured to the flattened end of the operating rod, a spring tending to urge the operating rod outwardly of the housing, a pressure member fitting said opening in the sidewall of the socket housing, the pressure member having a pair of tapered grooves on the underside thereof slideably receiving the edges of the tapered channel member, and a rubber sleeve positioned over the socket housing holding the pressure member in position.

9. A portrait studio light assembly comprising a light housing having a tubular passage extending therethrough, a reflector carried by the housing at an end thereof and having an opening at least of the same diameter as the tubular portion of the housing, a lamp assembly including a socket housing of generally tubular shape with generally flat end walls, one of the end walls fixed and the other removable and having a pair of openings therein, the socket housing having an opening in the sidewall thereof, a tube axially positioned in the socket housing and integral with the fixed end wall, a boss extending into the tubing, an incandescent lamp socket in the tube and abutting against the boss, a bracket attached to the lamp socket and having a threaded aperture, a handle member having a pair of openings therein, one of the openings in the removable end wall of the socket housing in alignment with one of the openings of the handle member, a threaded screw extending through said one of the openings of the handle member through said one of the openings of the removable end wall and engaging in the threaded aperture of the socket bracket holding the assembly together, a

guiding channel member slideable on the outer surface of the tube, a channel member with tapered edges in back-to-back relationship with the guiding channel member, an operating rod extending into the socket housing through the other of said openings of the removable end wall and through the other opening of the handle member, the channel members secured to the operating rod, a spring tending to urge the operating rod outwardly of the housing, a pressure member fitting said opening in the sidewall of the socket housing, the pressure member having a pair of tapered grooves on the underside thereof slideably receiving the edges of the tapered channel member, and a rubber sleeve positioned over the socket housing holding the pressure member in position.

10. A portrait studio light assembly comprising a light housing having a tubular passage extending therethrough, a reflector carried by the housing at an end thereof and having an opening at least of the same diameter as the tubular portion of the housing, a lamp assembly including a socket housing of generally tubular shape with generally flat end walls, one of the end walls fixed, the other removable and having a pair of openings therein, electronic flash tube socket means in the other end wall, the socket housing having an opening in the sidewall thereof, a tube axially positioned in the socket housing and integral with the fixed end wall, a boss extending into the tubing, an incandescent lamp socket in the tube and abutting against the boss, a bracket attached to the lamp socket and having a threaded aperture, a handle member having a pair of openings therein, one of the openings in the removable end wall of the socket housing in alignment with one of the openings of the handle member, a threaded screw extending through said one of the openings of the handle member through said one of the openings of the removable end wall and engaging in the threaded aperture of the socket bracket holding the assembly together, a guiding channel member slideable on the outer surface of the tube, a channel member with tapered edges in back-to-back relationship with the guiding channel member, an operating rod extending into the socket housing through the other of said openings of the removable end wall and through the other opening of the handle member, the operating rod having a flattened end, the channel members secured to the flattened end of the operating rod, a spring tending to urge the operating rod outwardly of the housing, a pressure member fitting said opening in the sidewall of the socket housing, the pressure member having a pair of tapered grooves on the underside thereof slideably receiving the edges of the tapered channel member, and a rubber sleeve positioned over the socket housing holding the pressure member in position.
